UNITED STATES PATENT OFFICE.

FREDERICK TURNER, OF LANSDOWNE, PENNSYLVANIA

DESIGN FOR A CHRISTMAS BANNER.

SPECIFICATION forming part of Design No. 25,984, dated September 8, 1896.

Application filed April 21, 1896. Serial No. 588,521. Term of patent 14 years.

To all whom it may concern:

Be it known that I, FREDERICK TURNER, a citizen of the United States, and a resident of Lansdowne, Delaware county, Pennsylvania, have invented a certain new and original Design for Christmas Banners, of which the following is a specification.

My design for a Christmas banner is fully shown in the accompanying drawings, in which—

Figure 1 represents the banner in the form of a flag, while Fig. 2 represents the banner in the form of a continuous strip.

The banner comprises two features, namely, the field A and the stripes B. The field A has a plain ground upon which is a representa-

tion of a star D, superposed upon which is a representation of a cross F. Each of the stripes is ornamented with a representation of a branch of holly with the leaves and berries, the branch running longitudinally along the stripe.

I claim—

The design for a Christmas banner, substantially as shown and described.

In testimony whereof I have signed my name to this specification in the presence of two subscribing witnesses.

FREDK. TURNER.
